STANCHION FOR ANIMAL-PENS.

1,163,440.

Specification of Letters Patent.

Patented Dec. 7, 1915.

Application filed November 20, 1913. Serial No. 802,070.

To all whom it may concern:

Be it known that I, ALBERT H. NELLER, a citizen of the United States, residing at

5 Fairfield, in the county of Jefferson and State of Iowa, have invented a new and useful Improvement in Stanchions for Animal-Pens, of which the following is a specification.

10 My invention relates to stanchions designed to be used principally in cattle pens and it consists of an improved plan of independently mounting the stanchion members in a panel of the pen, and of other features set forth in the specification and definitely 15 defined in the claims.

In the accompanying drawings forming a part of the specification, Figure 1 is a front view of a portion of a panel of a cattle pen embodying my invention, and showing the 20 stanchion in closed position. Fig. 2 is the same showing the stanchion in open position. Figs. 3, 4 and 5 are enlarged transverse sections on lines 3-3, 4-4 and 5-5 respectively of Fig. 1. Figs. 6 and 7 are 25 enlarged detail views.

Referring to the drawings, A represents a top-rail and B and B' upright railing or posts for the side of a cattle pen. The upper ends of the posts are connected to the 30 top-rail and their lower ends are set on or in a base or curb C which forms a foundation therefor. The posts B B' are spread apart to provide a suitable opening for a stanchion and a short horizontally disposed 35 member D, having its ends connected to the adjacent posts B near their lower ends, is placed in said opening. Vertically disposed stanchion members E are pivotally connected at their lower ends to castings F which 40 are secured to the member D and are provided on their upper ends with pivot bolts G which are preferably fitted with thimbles H upon which the stanchion members are mounted. (See Fig. 3).

45 The castings F are preferably made in two pieces F' and are clamped upon the member D by the bolts G and I, so they may be adjusted thereon the castings being shaped to clamp on the member D while 50 affording sufficient room for the free movement of the stanchion members on the pivots between their upper ends,—the thimble H

being the proper length to permit the bolt G to assist in clamping the castings F' on the member D.

55 The stanchion members are made the proper length to reach from the member D nearly to the top rail A, and plates J adapted to embrace and slide on the top rail are secured to the upper ends of the stanchion members by bolts L (see Fig. 4). The upper ends of the plates J are held together by bolts K which are preferably passed through thimbles M on which latch hooks N are pivoted as shown.

60 Two pairs of castings P are clamped upon the top rail A between the stanchion members E by means of bolts Q and R. The upper bolts R are preferably passed through thimbles S over which the latch hooks N 70 catch to hold the stanchion members in closed position. The upper edges of the latch hooks N are preferably fitted with ribs T by means of which they can be readily caught between thumb and finger and lifted 75 from the bolts R, (or thimbles surrounding the bolts), whereby the latch hooks will be freed from the castings P and the stanchion members will be permitted to move back to open position.

80 To close the stanchion members, all that is necessary is to push them in toward the castings P when the points of the hooks will slide over and catch behind the bolts R. The upper ends of the plates J are provided 85 with inwardly projecting lugs V which will prevent the hooks N from being lifted too high and thus insuring that they will always drop back into position to catch over the bolt R and lock the stanchion members in 90 closed position.

95 To prevent the animal from lifting the latch hooks with its horns or otherwise, guards U consisting of short straps of iron bent into a U shape with bolt holes in their ends, are inserted between the ends of the thimbles S and the castings P and are held in this position by the bolts R so as to effectually cover the outer ends of the hooks and prevent them from being lifted unless 100 they are caught by the ribs T. The posts B being set in a solid foundation and connected together by the top-rail and the member D to which the stanchion members

E are directly connected, makes an extremely strong construction capable of holding bulls or other strong animals.

The stanchion members are entirely independent of each other and are easily adjusted to suit different sizes of animals by loosening the bolts which hold the castings F and P, and sliding them closer together or farther apart on the member D and top rail A. In case it is not desired to extend the stanchion members up to the top rail, a horizontal member similar to D may be attached to the posts B below the top rail and the plates J and castings P may be mounted on this member as they are on the top rail as will be readily understood by those skilled in the art. The pen is usually made of four panels having their ends joined together at right angles to hold a single animal and the stanchion is placed in one of the panels only.

The posts to which the member D is connected must be spaced apart a sufficient distance to afford room for and permit the free movement of the stanchion members. It is preferable that the top rail A, posts B and B', horizontal member D and the stanchion members E be made of tubular metal, as shown in the drawings, but they may be made of any other suitable material without departing from the spirit of my invention.

What I claim is:

1. In animal pens comprising a curb, top rail, and vertical posts, all of which posts are set in the curb and connected to the top rail, two of said posts specially spaced, a horizontally-disposed member secured at its ends near the lower ends of said specially spaced posts, a pair of stanchion members hingedly connected at their lower ends to the horizontally-disposed member at approximately uniform distances from the specially spaced posts, with connections at their upper ends arranged to slide back and forth on the top rail; whereby the stanchion members may be opened and closed, and means for holding said stanchion-members in closed position.

2. In stanchions for animal pens having a series of vertically disposed posts and a horizontally disposed rail connecting the adjacent posts together at or near their upper ends, a horizontally disposed member connected to the adjacent posts near their lower ends, a pair of stanchion members spaced apart and adjustably pivoted at their lower ends to the horizontal member, plates adapted to straddle and slide on the upper horizontal rail applied to the upper ends of the stanchion members, catches slidably

applied to the upper rail between the stanchion members, and latch hooks pivoted to the upper ends of the aforesaid plates above the rail so as to hook over the catches and hold the stanchion members in closed position.

3. In a device of the character described, vertically disposed posts connected together at or near their upper ends by a horizontal rail, a horizontally disposed member connected to the adjacent posts near their lower ends, clamp castings adjustably secured to said horizontal member, a pair of vertically disposed stanchion members spaced apart and pivoted at their lower ends to said clamp castings, plates secured to the upper ends of the stanchion members and adapted to surround and slide on the upper horizontal rail, catches adjustably secured to said rail between the stanchion members and slidably adjustable thereon, latch hooks pivoted to the plates on the stanchion members and adapted to hook over the catches and hold the stanchion members in closed position, and U-shaped guards applied to the catch plates above the upper rail to protect the outstanding ends of the latch hooks.

4. In a device of the character described, upright posts having their upper ends connected together by a horizontal rail, a pair of stanchion members spaced apart and pivoted at their lower ends to a suitable support and their upper ends fitted with plates adapted to embrace and slide on the upper rail, catch castings applied to the upper rail, latch hooks pivoted to the upper ends of the aforesaid plates, above the top rail, and inwardly projecting lugs on the upper ends of the plates adapted to prevent the latch hooks from being raised too high.

5. In a device of the character described, a top rail, a stanchion member pivoted at its lower end and provided at its upper end with plates embracing and slidable on the top rail, a pair of clamping members having an open space between their upper ends applied to the top rail, bolts passed through the upper and lower ends of said members to clamp them upon the rail, a thimble inserted between the upper ends of the members and encircling the bolt therethrough, and a latch pivoted to the upper ends of the stanchion plates and adapted to catch over the thimble and hold the stanchion member in a closed position.

Fairfield, Iowa, Nov. 18, 1913.

ALBERT H. NELLER.
